FUEL PUMP DELIVERY VALVE

William M. Nichols, Schenectady, N. Y., assignor
to American Locomotive Company, New York,
N. Y., a corporation of New York

Application September 7, 1950, Serial No. 183,556

4 Claims. (Cl. 137—512.1)

1

This invention relates to fuel injection pumps for compression-ignition engines.

In fuel injection pumps of the class wherein the injection plunger has a controlling edge to determine the effective length of the pump stroke and a spring controlled displacer type check valve which closes upon the spill-back of fuel through the plunger, the rate of such closing is so rapid that a negative pressure wave is induced in the fuel delivery pipe during the closing movement which is characterized by a curve having a very steep slope. When the valve strikes the seat at the end of the closing movement, a positive pressure wave is induced in the fuel delivery pipe. Both the positive and negative waves travel at the velocity of sound through the delivery pipe. These waves, upon reaching the injector, disturb its normal intended performance. The negative wave results in the passing of combustion gases from the combustion chamber past the fuel injector seat into the nozzle chamber thereby causing deterioration to the injector. The positive wave results in a re-opening of the valve in the fuel injector thus allowing fuel to pass into the combustion chamber under unfavorable conditions.

The principal object of the invention is to provide means to control the velocity of the seating movement of such a delivery and check valve and also to cushion or minimize the force with which the valve strikes the seat, thereby to avoid jarring the pumping mechanism and also to change the slope of the pressure waves to eliminate their objectionable features. A more specific object is to provide such a valve with a dash pot device to accomplish such purposes. Still another object is to provide such a valve with a dash pot device, and having an internal relief valve to minimize retardation of the reverse action of the dash pot. Other and further objects of the invention will appear from the following description, the accompanying drawings and the appended claims.

In the drawings, Fig. 1 shows a fragmentary sectional view of a fuel pump assembly, the injector and delivery line being diagrammatic; Fig. 2 is an enlarged view of the valve in its housing; and Fig. 3 is a sectional view of the valve with the relief valve illustrated.

In the drawings, the invention is shown applied to a fuel injection system for a compression-ignition engine. Casing 10 has an axial bore 11 in which is arranged a sleeve 12 to provide a cylinder 13 for pumping plunger 14, the latter being reciprocated in the cylinder in conventional manner by the alternate action of a cam shaft and a return spring, not shown. Disposed in bore 11 in contiguity with sleeve 12 is a flanged valve housing member 15 which is maintained in position by plug 16, such plug being threaded

2

into the casing. Housing 15 (Fig. 2) has a central bore 17, a conical valve seat 18, and a cylindrical duct 19 which connects bore 17 to cylinder 13. Delivery valve 20 is arranged in bore 17 and extends into duct 19. Annular sealing gasket 21 is disposed between flange 22 of housing 15 and the inner end of plug 16.

Fuel is supplied under pressure to cylinder 13 from an outside source through annular port 23 and radial passages 24. Plunger 14 on its upward stroke forces fuel from cylinder 13 through duct 19, valve 20, chamber 25, passage 26, and delivery line 27 to the fuel injector 28. Plunger 14, which has a constant stroke, is provided with a helical edge 29 of conventional construction. Edge 29 controls the effectiveness of the piston stroke by providing for a spill-back of the fuel from cylinder 13 through radial passages 24 and port 23. The amount of fuel supplied to the injector will be varied according to the position of the helical edge of the plunger as the latter may be controlled by the engine governor (not shown). Valve 20 is normally maintained upon its seat 18 by return spring 33, the latter being preloaded in chamber 25 between plug 16 and valve flange 31. Discs 32 of desired thickness are inserted in chamber 25 at the top of spring 33 upon original assembly in order to adjust its tension. Other suitable means to provide such adjustment will suggest themselves to one skilled in the art.

Valve 20 has a main body 33, a cylindrical flange 31 connected to the body by a portion 34 of reduced diameter, a conical shoulder 35 for seating purposes, and an extension 36 beyond the conical seat connected to the main body by neck 37. Valve body 33 is fluted to provide lands 38 to guide the valve in bore 17 and also to provide longitudinal passages 39 to permit the transfer of fuel therethrough. Extension 36 is likewise fluted to provide guiding lands 40 and fuel passages 41. Extension 36 also includes a cylindrical portion 42 of reduced diameter adjacent neck 37. The peripheral surface of portion 42 is smooth and is spaced slightly from the wall 43 of duct 19 when the valve is moving to seated position (see Fig. 1). A restricted annular passageway 44 is thereby provided for purposes hereinafter more fully described. Cylindrical flange 31 is precision machined to form a close sliding fit with bore 17 thereby to prevent the passage of fuel through the bore whenever the flange is positioned therein. As appears from an inspection of Figs. 2 and 3, the axial distance between flange 31 and seating shoulder 35 is less than the axial distance from the delivery end 17a of the bore 17 and the seat 18.

When the spill-back action through plunger 14 begins, pressure in the fuel column extending from the plunger to the injector will drop in-

stantly, and valve 20 will move toward its seat in response to the bias of return spring 38 and the expansion of the fuel compressed in the column. During such valve movement, flange 31 will entrap fuel in bore 17. Such fuel has no 5 means of escape except through duct 19, but access of the fuel to the duct is only through the restricted passage 44. A dash pot device is thus produced in which a fluid cushion is provided between the valve and its seat, and the motion of 10 the valve is retarded, thereby avoiding the jarring effect which normally results to the pump assembly when the valve strikes the seat. The slope of the negative pressure wave will thereby be lessened so that the combustion gases will not 15 pass the injector valve seat, and the positive pressure wave will be minimized to the extent that it will not lift the injector valve. It should here be observed that for best performance the restricted passage should be so designed that the 20 valve will seat before the completion of the pumping stroke of the plunger.

When plunger 14 completes a cycle and again moves toward valve 20, pressure builds up rapidly once the plunger closes radial passages 24, 25 and the valve is thereupon lifted by the fuel against the opposition of spring 39. Due to the limitations of the restricted passage 44, a region of low pressure will form in bore 17 upon the opening movement of the valve, and the valve 30 will be retarded until portion 42 clears wall 43 axially. Such an arrangement may be desirable when the engine is operating at low speeds. In the case of an engine operating at high speeds, however, it may be preferred to eliminate such retardation. To accomplish this result, a relief valve, generally indicated at 45 (Fig. 3), is provided within valve 20. Such relief valve may be of conventional design, as, for example, one comprising a ball 46 disposed upon a conical seat 47 formed at the end of inlet passage 48 and a return spring 49 arranged in bore 50 and maintained against the ball by the nut 51 threaded into valve flange 31. Spring 49 offers only slight opposition to the movement of the ball so that fuel in duct 19 will pass through passage 48, bore 50, and radial ports 52 to relieve the vacuum or region of low pressure just described. Other types of relief valves will readily suggest themselves to one skilled in the art.

While there have been hereinbefore described approved embodiments of the invention, it will be understood that many and various changes and modifications in form, arrangement of parts and details of construction thereof may be made without departing from the spirit and scope of the present invention, and that all such changes and modifications as fall within the scope of the appended claims are contemplated as a part of this invention.

What I claim is:

1. A delivery valve apparatus for controlling the intermittent flow of a fluid column from a pressure cylinder to a point of use comprising a housing having a first bore, a valve seat in the housing spaced at a predetermined distance from the delivery end of said bore, a second bore axially aligned with the first bore, and a valve reciprocably guided in the bores, said valve having a main body reciprocable in the first bore, a passage in the body to permit the movement of fluid therethrough, a cylindrical flange on the body, a seating portion on the body, and a cylind-

rical extension on the body beyond the seating portion and reciprocable in the second bore, the flange having a fluid sealing fit in the first bore and being spaced from the seating portion at a lesser distance than the distance between the valve seat and the delivery end of the first bore so that when the valve is moved toward seated position the flange enters the bore before the valve seats thereby to force fluid in the first bore past the seat, and the cylindrical extension being spaced from the wall of the second bore to form a restricted passageway to retard the passage of the fluid thus forced by said flange so that the fluid thus entrapped will cushion the valve in its seating movement and damp surges arising in the fluid column.

2. A delivery valve apparatus for controlling the intermittent flow of a fluid column from a pressure cylinder to a point of use comprising a housing, a first bore therein, a second bore aligned with the first bore, a valve seat spaced at a predetermined distance from the delivery end of the first bore, a valve arranged in the bores, and a return spring for the valve, the valve having a body slidably mounted in the first bore, a fluid passage through the body, a cylindrical flange on the body having a fluid sealing fit with the first bore and being spaced from the seating portion at a lesser distance than the distance between the valve seat and the delivery end of the first bore, said valve being adapted to move out of the first bore during the passage of fluid therethrough in one direction but to return thereto upon the completion of such passage to capture fluid in said bore, an extension on the body reciprocable in the second bore, a fluid passage through the extension, and a cylindrical portion on the extension, the peripheral face of which is spaced from the wall of the second bore to form a restricted annular fluid passage as the extension reciprocates therein thereby to provide a dash pot to retard the seating movement of the valve and to damp surges arising in the fluid column after the completion of fluid passage.

3. A valve, according to claim 1, in which the valve is provided with relief means adapted to establish communication between the fluid column on opposite sides of the valve seat when the fluid is passing from the pressure cylinder to the point of use.

4. A valve, according to claim 1, provided with a relief valve within its body comprising a duct in communication with the fluid supply, a bore in communication with the duct, a ball valve between the duct and the bore, a return spring in the bore, and a passage between the bore and the fluid column beyond the valve seat whereby communication is established through the valve when fluid passes from the pressure cylinder to the point of use.
